UNITED STATES PATENT OFFICE

135,935

DESIGN FOR A FRAMEWORK FOR PHYSICAL AND RECREATIONAL TRAINING

Warren P. Miller, Anderson, Ind.

Application May 5, 1943, Serial No. 110,130

Term of patent 14 years

To all whom it may concern:

Be it known that I, Warren P. Miller, a citizen of the United States of America, residing at Anderson, county of Madison, State of Indiana, have invented a new, original, and ornamental Design for a Framework for Physical and Recreational Training, of which the following is a specification, reference being had to the accompanying

drawing, forming part hereof, and wherein the single figure is a perspective view of the framework for physical and recreational training showing my new design.

I claim:

The ornamental design for a framework for physical and recreational training, as shown.

WARREN P. MILLER.
